ROLLING OR SLIDING CARD FILE

Albert J. Kotcher, Detroit, Mich., assignor to
Chrysler Corporation, a corporation of Delaware

Application January 6, 1933, Serial No. 650,457

4 Claims. (Cl. 45—2)

My invention relates to office equipment and particularly to equipment employed for the filing and storage and various types of cards in containers adapted to render them readily accessible to the operator thereof. More particularly, my 5 invention relates to a novel type of filing card cabinet, and to a combination of such cabinet and a table or writing desk adapted to be used in conjunction therewith.

Heretofore, it has been customary to employ 10 ordinary filing cabinets in which a series of drawers are disposed in stacked relation and at various heights within which are filed cards, or the like containing information. When it was necessary to secure information from those cards it was customary to remove the card from the file 15 and carry it to a suitable writing desk or the like where the desired information was taken therefrom. This type of equipment is objectionable because the various drawers are disposed at various heights and it is impossible to provide a suitable table top or the like so disposed with respect 20 to the various heights or drawers that the information may be taken therefrom conveniently without bodily movement on the part of the operator.

By my invention I have eliminated the necessity 25 for the operator to move from a single position by providing a cabinet and a table associated therewith in such manner that all of the cards are presented to the operator at a uniform height and at a height with respect to the height of the table which facilitates copying information therefrom.

One object of my invention consists in providing 30 a novel combination of filing cabinet and table which expedites the copying of information from the various cards with a minimum of effort on the part of the operator.

Another object of my invention consists in providing 35 a novel type of filing cabinet in which all of a very large number of cards are disposed at a uniform height and are presented to the eye of a stationary operator in substantially uniform positions.

A third object of my invention consists in providing 40 a novel combination of filing card cabinet and table wherein the table is substantially equal in height to the tops of all of the cards contained within the cabinet.

For a better understanding of my invention, 45 reference may now be had to the accompanying drawing, of which:

Fig. 1 is a plan view of a portion of a filing cabinet constructed in accordance with my invention.

Fig. 2 is a side elevational view of the structure 5 illustrated in Fig. 1.

Fig. 3 is a cross-sectional view of the structure 10 illustrated in Fig. 1, the section being taken along the line III—III thereof.

Fig. 4 is a perspective view of one of the card 15 containing trays employed in the cabinet and constructed in accordance with my invention.

Fig. 5 is a cross-sectional view illustrating one 20 complete card containing tray and a portion of a second tray mounted in position on the large tray or cabinet illustrated in Fig. 1.

Fig. 6 is a plan view of a pair of filing cabinets 25 and an intermediately disposed desk or table adapted for the use of a number of operators simultaneously illustrating one manner in which a battery of filing cabinets may be arranged.

In the structure illustrated in the drawing is a relatively long rectilinear tray 1 provided with supporting legs 2. Mounted on this tray are a plurality of relatively short rectilinear trays or 30 cars 3 adapted for the reception of filing cards. Each of these short trays is provided with downwardly extending flanges 4 on each side thereof on which are mounted roller members or wheels 6 which engage and are supported by track members 5 mounted in the long tray 1.

The long tray 1 comprises a flat substantially 35 horizontal bottom portion 10 and four side walls 11 secured thereto. These side walls are vertically disposed and serve to confine the movement of the cars 3 therebetween. The upper edges of the side walls 11 are each curved into a bead, as illustrated at 12, which provides a relatively strong edge and presents a smooth surface, thus preventing injury 40 to the hand of the operator. The track members 5 are secured to the bottom portion 10 of the tray 1.

Each of these track members consists of a flat horizontally disposed portion 13 on which the wheels 6 roll and integral flange portions 14 which 45 serve as a guide to the rollers 6, thus keeping the movement of the cars 3 parallel to the sides of the large tray 1. Of those tracks 5 disposed in the central portion of the tray 1, the flanges 14 may be connected together, as illustrated at 15. The flange portions 14 of the two tracks at the sides 50 of the tray 1 are connected to the side walls 11 by a connecting portion 16, thus adding to the rigidity of the tray.

The short trays or cars 3 each comprises a bottom portion 20 and integral side walls 21 at the 55 sides and ends thereof. Partition members 22 serve to divide the cards disposed in the trays 3 into groups or divisions. The downwardly extending flanges 4 which support the wheels or

rollers 6 constitute a portion of a sheet metal member of Z shape cross-section, a central portion 23 of which engages the bottom portion of the tray 3 adjacent the side edges and the other leg 5 24 of which engages the side wall 21, thus constituting a reinforcing member for the tray 3.

As illustrated in Fig. 6, the trays 1 are intended to contain a plurality of the short trays 3, which are approximately half, or slightly more than 10 half, of the length of the trays 1, the object being that an operator situated at approximately the central portion of the length of the tray 1 may move the trays 3 longitudinally thereof, thus presenting each of the filing cards to the eye of the 15 operator at approximately the same point and the same height. Two or more long trays 1 may be arranged in spaced side-by-side relationship with a table top or desk 30 located therebetween and intermediate their ends for the convenience of an 20 operator. The table top 30 is preferably secured to the inner side wall of adjacent long trays but it may be stationarily located with respect to the long trays in any suitable manner.

It will be apparent that this arrangement of the 25 table top and the movable trays 3 gives to the operator ready access to the large number of cards contained in each of the trays 3 which are presented to his eye at a glance and in such position as to facilitate the copying of information therefrom onto paper disposed on the table top 30. The 30 relative lengths of the long trays 1 and short trays 3 permit all portions of the short trays of the various adjacent long trays to be transversely aligned within the front and rear bounding planes of the table, thus permitting an operator to conveniently compare the data of a plurality of cards located in diverse short trays.

Although I have illustrated but a single form of my invention and have described in detail several 40 applications thereof, it will be apparent to those skilled in the art that my invention is not so limited but that various modifications and changes may be effected therein without departing from the spirit of my invention or from the scope of the 45 appended claims.

What I claim is:

1. A filing cabinet comprising a relatively long rectilinear tray comprising a substantially horizontal bottom portion and substantially vertical walls, and a plurality of relatively short rectilinear trays disposed within said long tray in side-by-side relationship, said short trays being individually movable longitudinally of said long tray. 5

2. A filing cabinet comprising a relatively long 10 rectilinear tray comprising a substantially horizontal bottom portion and substantially vertical walls, a plurality of pairs of tracks disposed on said bottom portion and extending longitudinally thereof, and a plurality of relatively short rectilinear trays disposed within said long tray in side-by-side relationship, each of said short trays 15 being mounted on a pair of tracks and being movable longitudinally thereon relative to each other and longitudinally of said long tray. 20

3. A filing cabinet comprising a relatively long rectilinear tray comprising a substantially horizontal bottom portion and substantially vertical walls, a plurality of pairs of tracks disposed on said bottom portion and extending longitudinally 25 thereof in side-by-side relationship, and a plurality of rectilinear trays of substantially half the length of said long tray disposed therein, said short trays being adapted for the reception of filing cards disposed transversely therein, each 30 of said short trays being disposed on a pair of said tracks and being movable longitudinally thereon relative to each other.

4. A filing cabinet comprising a relatively long rectangular tray, a plurality of comparatively 35 short trays disposed in said long tray in side-by-side relationship, and means shiftably supporting said short trays on said long tray and confining the movement of said short trays to a course extending longitudinally of said long tray, said 40 short trays being movable relative to each other and substantially all portions thereof being alignable transversely with each other within a section of said long tray.

ALBERT J. KOTCHER. 45
